(57) **CLAIM**

The ornamental design for a mobile phone, as shown and described.

DESCRIPTION

FIG. 1 is a perspective view of a mobile phone showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a perspective view thereof showing the state that when folding the subject design in half, the back cover part is pushed aside and then the transparent part on the front left side can be seen at the back side;

FIG. 9 is a perspective view thereof in which the subject design is folded in half;

FIG. 10 is a front view of FIG. 9;

FIG. 11 is a rear view of FIG. 9;

FIG. 12 is a left side view of FIG. 9;

FIG. 13 is a right side view of FIG. 9;

FIG. 14 is a top plan view of FIG. 9;

FIG. 15 is a bottom plan view of FIG. 9; and,

FIG. 16 is a front view of FIG. 9 showing an example of the usage of the subject design.

The broken lines shown in the figures that are immediately adjacent to the areas included in the claim represent the bounds of the claim. The broken lines in FIG. 16 that occur within the boundaries of the claim show an example of the mobile phone in a state of operation. The broken lines form no part of the claimed design.
